(57) **CLAIM**

The ornamental design for an apparatus for treatment of
shower water, as shown and described.

DESCRIPTION

FIG. 1 is an upper left front perspective view showing my
new design;

FIG. 2 is an exploded upper left front perspective view
thereof;

FIG. 3 is a front elevational view thereof;

FIG. 4 is a a right side elevational view thereof, the left side
being a mirror image thereof;

FIG. 5 is a rear elevational view thereof;

FIG. 6 is a top plan view thereof; and,

FIG. 7 is a bottom plan view thereof.

The broken lines shown in FIGS. 1-7 show magnets, a sleeve
that covers the apparatus, internal rifling, a disk, a large
diameter set of threads onto which the sleeve is attached, and
a smaller diameter set of threads for attachment of the device
to a shower head, all of which form no part of the claimed
design.
